US00D807983S

(12) **United States Design Patent** (10) **Patent No.:** **US D807,983 S**
(45) **Date of Patent:** **** Jan. 16, 2018**

(54) **SCOPE**

(71) Applicant: **Charles Shi**, Walnut, CA (US)

(72) Inventor: **Charles Shi**, Walnut, CA (US)

(73) Assignee: **All Pro Sporting Goods Inc.**, Mira Loma, CA (US)

(**) Term: **15 Years**

(21) Appl. No.: **29/574,236**

(22) Filed: **Aug. 12, 2016**

(51) LOC (11) Cl. **22-01**

(52) U.S. Cl.

USPC **D22/109**

(58) **Field of Classification Search**

(57) **CLAIM**

The ornamental design for a scope, as shown and described.

DESCRIPTION

FIG. 1 is a left perspective view a scope;

FIG. 2 is a right perspective view of a scope;

FIG. 3 is an end view of the scope taken from a perspective of a right end of the scope;

FIG. 4 is an end view of the scope take from a perspective of a left end of the scope;

FIG. 5 is a top view of the scope taken from a perspective of a left side of the scope;

FIG. 6 is another top view of the scope taken from a perspective of a right side of the scope; and,

FIG. 7 is another top view of the scope looking straight down at the scope.

The broken lines in the drawings are used to illustrate unclaimed portions of the scope and form no part of the claimed design.

1 Claim, 4 Drawing Sheets
